UNITED STATES PATENT OFFICE.

EDWARD A. CUNNIFF, OF WALTHAM, MASSACHUSETTS, ASSIGNOR TO DRAPER CORPORATION, OF HOPEDALE, MASSACHUSETTS, A CORPORATION OF MAINE.

SELVAGE-RELIEVING MECHANISM FOR LOOMS.

Application filed July 25, 1927. Serial No. 208,179.

This invention relates to means for relieving the strain on the selvage warps during the operation of weaving cloth in a loom.

The object of the invention is to provide 5 for the advancement of the fell at the selvage prior to beat-up so that when the pick is beaten in, the fell shall extend in a substantially straight line.

The object of the invention is further to 10 provide mechanism in connection with the usual temple for effecting the advancement of the selvage prior to beat-up so as to relieve the chafing and strain of the reed on the selvage warps.

15 The object of the invention is further to provide a selvage strain-relieving mechanism which will assist in maintaining the cloth stretched widthwise as it advances in the weaving operation.

20 These and other objects and features of the invention will appear more fully from the accompanying description and drawings and will be particularly pointed out in the claims.

A simple and preferred form of construction 25 embodying the invention is herein shown as secured to and operating in conjunction with a loom temple. With such a construction it will be understood that the parts are duplicated but reversed at the opposite 30 side of the loom and that it is therefore sufficient to describe the mechanism at but one side of the loom.

In the drawings:

Fig. 1 is a top plan view of a portion of 35 a loom embodying a simple and preferred form of the present invention and with the reed nearing the conclusion of the beat-up.

Fig. 2 is a view similar to Fig. 1 with the reed in an earlier stage of its movement.

40 Fig. 3 is a view chiefly in vertical cross section taken on the line 3—3 of Fig. 1.

Fig. 4 is a detail chiefly in vertical cross section taken on the line 4—4 of Fig. 2.

Fig. 5 is a view in perspective of the lever 45 and auxiliary roll.

During the operation of weaving, the cloth shrinks widthwise and means are universally provided, such as the well known temple constructions, which act to maintain the 50 cloth stretched widthwise as it advances in the weaving operation and to secure a substantially uniform width of the cloth as it is wound up on the cloth roll. But the width of the cloth, notwithstanding the use 55 of such temples or stretching mechanism,

is always much narrower than the width of the sheet of warps passing through the reed, which is the instrumentality employed to beat in each successive pick of weft or filling. While, therefore, there is little strain on the 60 warps at the center of the cloth being woven, the strain increases toward the selvage and at the selvage is very substantial because the selvage warps necessarily extend in an inclined direction toward the center of the 65 cloth from the front face of the reed to the fell. It is common, therefore, to make the selvage warps of heavier yarn and to space them more closely. Because of this and of the forces acting in the weaving operation the fell of the cloth at the selvage, 70 before beat-up occurs, is found to stand somewhat in the rear of the general line of the fell. The amount of this deviation of the line of the fell rearwardly at the selvage 75 depends upon the character of the goods being woven, the tension to which the warps are subjected, the character of the selvage warps and other factors familiar to those skilled in the art, but in many cases this 80 deviation is quite pronounced. When, therefore, the reed beats in the pick, it does not strike the fell evenly throughout but strikes first against the fell at the selvages, thus forcing the cloth at the selvages forwardly 85 and straining and wearing the selvage warps.

The present invention acts automatically to advance the fell of the cloth at the selvage prior to each beat-up so that the fell will 90 extend in a substantially straight line and be engaged evenly throughout by the reed as it beats in the pick. The fell at the selvage may even be advanced farther than the fell at the central portion of the cloth, if 95 desired, so that the reed will first engage the central section of the fell as it beats in the pick.

The operation of the invention is found materially to relieve the wear and strain on 100 the selvage warps, to reduce the breakage of the selvage warps, and greatly to improve the character of the weaving.

The preferred mechanism employed also assists the temple in maintaining the cloth 105 stretched widthwise. Such a mechanism in no way interferes with the construction or operation of the loom and may readily be applied to existing looms.

The invention may be involved in almost 110

any type of loom and as the construction and operation of the loom itself is well known and familiar to those skilled in the art, it is only necessary to illustrate and describe 5 those portions of a loom directly concerned with the present invention.

The breast beam 1 of a loom is shown having secured thereto the bracket 2 and stand 3 of an ordinary type of temple. The 10 temple illustrated has the usual head 4 provided with the shank 5 sliding in the stand and yieldingly projected rearward. The head presents the pod 6 and cap 7 between which are mounted the usual temple roll 15 or rolls, herein shown as two in number. These temple rolls 8 are journaled in the temple head so as to stand transversely of the cloth and their peripheral surfaces act to engage and hold the cloth, being usually 20 provided with radially projecting pins, as illustrated. A heel 9 depends from the temple head in the path of the lay 10.

The lay 10 is carried by the lay swords 11, which also support the usual reed 12. Adjacent the breast beam the loom is provided with suitable means such as the roll 13 for taking up or winding up the completed cloth.

The sheets of warps 14 extend forwardly 30 from the warp beam and the shed forming and other usual mechanisms of the loom between the dents of the reed 12 to form the cloth which, after it is formed, passes through the temple head about the temple 35 rolls 8 and thence forward to the take-up roll 13. After the pick of weft 15 has been carried through the warps by the shuttle, the lay beats or carries the reed 12 forwardly 40 against the fell 16 with a sharp blow, thus forming the cloth. The cloth necessarily contracts in width, as already pointed out, and the temples act to maintain it stretched widthwise to the required degree to secure a desirable and uniform width of the finished cloth on the take-up roll. It will be 45 seen that the selvage warps 17, which are herein shown as of heavier yarn than the main body of warps 14, extend from the face of the reed in an angular direction toward the center of the cloth and, as shown in 50 Fig. 2, the portion of the fell at the selvage, due to the conditions existing, stands rearward of the general line of the fell. This portion of the fell is advanced just prior to 55 each beat-up by this invention so as to relieve as much as possible the strain and wear on the selvage warps as the reed beats the pick in.

This result is secured by providing means 60 which act on the cloth at the selvage forward of the usual stretching means such as the temple and prior to the beat-up to advance the fell at the selvage when the beat-up occurs. For this purpose a simple and 65 effective means is shown mounted upon the

temple and actuated by the lay. A lever having an auxiliary cloth engaging roll, shown separately in Fig. 5, is fulcrumed on the temple shank 5. This lever is of the bell crank form fulcrumed at 18 on a stud 19 projecting laterally from the temple stand, and has one arm in the form of a depending heel 20 and the other arm 21 bifurcated to receive the journal 22 of the auxiliary cloth engaging roll 23. The periphery of this roll is preferably provided with radially projecting pins to engage the cloth after the manner of the usual temple roll. The lever normally stands in the position shown in Fig. 4 with its heel 20 rearward of the temple heel 9 so that the roll 23 in engagement with the cloth presses lightly against the cloth at the selvage portion. The lever is held in this position by a spring 24 hooked about a stud 25 projecting laterally from the heel 20 and coiled at its upper end about a stud 26 on the temple stand 5 and locked at its extreme end against another stud 27.

As the lay moves forward carrying with it the reed, it first engages the heel 20 of the auxiliary roll carrying lever and rocks this lever until the lay comes in engagement with the heel 9 of the temple. During this movement the auxiliary cloth engaging roll 23 is moved bodily against the cloth to bend the selvage portion transversely, or in this case upwardly, and this acts to advance the cloth at the selvage by pulling it forward through the temple. The parts are so arranged that this movement is sufficient either to pull the fell at the selvage into line with the main line of the fell, as shown in Fig. 1, or even to pull it slightly farther forward, if desired. As the lay concludes the beating up movement, the temple moves forward slightly, thus without disturbing the action of the auxiliary cloth engaging roll and the pick is beaten in by the reed uniformly and evenly and with a minimum amount of strain and wear on the selvage warps. As the lay beats back, the auxiliary cloth engaging roll and its carrying lever return, under the action of the spring 24, to normal position ready for the next beat-up.

With a cloth engaging roll of the construction illustrated, that is, with a holding peripheral surface such as that provided by the radially projecting pins, this roll assists to maintain the cloth stretched widthwise after the manner of the temple rolls.

Having thus described the invention, what is claimed as new, and desired to be secured by Letters Patent, is:

1. A loom comprising means acting on the cloth forward of the fell to maintain the cloth stretched widthwise as it advances in the weaving operation, and means acting on the cloth at the selvage forward of the stretching means prior to beat-up to advance

the fell at the selvage when beat-up occurs.

2. A loom comprising means acting on the cloth forward of the fell to maintain the cloth stretched widthwise as it advances in the weaving operation, and means acting on the cloth at the selvage forward of the stretching means prior to beat up to bend the selvage portion transversely and thus to advance the fell at the selvage when beat-up occurs.

3. A loom comprising means acting on the cloth forward of the fell to maintain the cloth stretched widthwise as it advances in the weaving operation, a roll located forward of the stretching means at the selvage and engaging the face of the cloth in substantial parallelism with the fell and means acting prior to beat-up to move the roll bodily against the cloth to bend the selvage portion transversely and thus to advance the fell at the selvage when beat-up occurs.

4. A loom comprising the construction defined in claim 3 in which the cloth engaging roll is provided at its peripheral surface with radially projecting pins acting to assist in maintaining the cloth stretched widthwise as the cloth advances in the weaving operation.

5. A loom comprising rotatable means engaging the cloth at the selvage forward of the fell to maintain the cloth stretched widthwise while permitting the cloth to advance in the weaving operation, a roll located forward of said rotatable means at the selvage and engaging the face of the cloth in substantial parallelism with the fell, and means acting prior to beat-up to move the roll bodily against the cloth to bend the selvage portion transversely and thus to advance the fell at the selvage when beat-up occurs.

6. A loom temple comprising a frame having a head and a depending heel engaged by the lay upon the beat-up, a cloth engaging temple roll journalled in the head, and an auxiliary cloth engaging roll journalled on the frame forward of and parallel to the temple roll and bodily movable with respect to the frame transversely of the cloth at the selvage.

7. A loom temple comprising a frame having a head and a depending heel engaged by the lay upon the beat-up, a cloth engaging temple roll journalled in the head, a support movably mounted on the frame and having a heel normally standing rearward of the frame heel and an auxiliary cloth engaging roll journalled on the support and extending across the path of the selvage forward of and parallel with the temple roll, the said

support, when the temple is mounted on a loom and the lay beats up striking the heel of the support, moving the auxiliary roll bodily to cause it to bend the selvage transversely and thus advance the fell at the selvage before the pick is beaten in.

8. A loom temple comprising the construction defined in claim 7, in which the auxiliary cloth engaging roll is provided at its peripheral surface with radially projecting pins acting to assist in maintaining the cloth stretched widthwise as it advances in the weaving operation.

9. A loom temple comprising a frame having a head and a depending heel engaged by the lay upon the beat-up, a cloth engaging temple roll journalled in the head, a lever fulcrumed on the frame having one arm forming a heel normally standing rearward of the frame heel, an auxiliary cloth engaging roll journalled on the other arm of the lever and extending across the path of the selvage forward of and parallel with the temple roll, whereby when the temple is mounted on a loom and the lay beats up, the lay will strike the lever heel and rock the lever to cause the auxiliary roll to bend the selvage transversely and thus advance the fell at the selvage before the lay engages the frame heel and the pick is beaten in.

10. A loom temple comprising the construction defined in claim 9, in which the auxiliary cloth engaging roll is provided at its peripheral surface with radially projecting pins acting to assist in maintaining the cloth stretched widthwise as it advances in the weaving operation.

11. A loom temple comprising a frame having a head and a depending heel engaged by the lay upon the beat-up, a cloth engaging temple roll journalled in the head, a lever fulcrumed transversely on the frame and having one arm in the form of a heel extending adjacent the frame heel, a spring normally acting to position the lever with its heel standing rearward of the frame heel, an auxiliary cloth engaging roll journalled on the other arm of the lever and extending across the path of the selvage forward of and parallel with the temple roll, whereby, when the temple is mounted on a loom and the lay beats up, the lay will strike the lever heel and rock the lever to cause the auxiliary roll to bend the selvage transversely and thus advance the fell at the selvage before the lay engages the frame heel and the pick is beaten in.

In testimony whereof, I have signed my name to this specification.

EDWARD A. CUNNIFF.
